UNITED STATES PATENT OFFICE.

HARRY KATIMS AND EMIL WEINER, OF NEW YORK, N. Y.

DESIGN FOR A TEXTILE FABRIC.

Application filed May 12, 1928. Serial No. 26,654. Term of patent 7 years.

To all whom it may concern:

Be it known that we, HARRY KATIMS and EMIL WEINER, both citizens of the United States, residing at New York, in the county of New York and State of New York, have invented a new, original, and ornamental Design for a Textile Fabric, of which the following is a specification, reference being had to the accompanying drawing.

The figure is a face view of a textile fabric showing our new design.

We claim:

The ornamental design for a textile fabric as shown.

In testimony whereof we have affixed our signatures.

HARRY KATIMS.
EMIL WEINER.
